WHEELED ACROBATIC FIGURE TOY

Richard Regenburgh, Sr., Totowa Boro, N. J.

Application September 23, 1938, Serial No. 231,443

5 Claims. (Cl. 46—107)

This invention relates to toys, and its general object is to provide a wheeled toy that includes figures mounted to perform acrobatic movements, and the mounting means thereof is associated with the wheels in a manner to cause said movements when the toy is propelled either forward or backward, with the result it will be obvious that my toy will provide much fun and amusement especially for a child, as it is being pushed or pulled thereby.

A further object is to provide a wheeled acrobatic figure toy that can be propelled with minimum effort, is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary side elevation of the toy which forms the subject matter of the present invention.

Figure 2 is a sectional view taken approximately on line 2—2 of Figure 1, looking in the direction of the arrows.

Referring to the drawing in detail, it will be noted that my toy in the form as shown, includes a wagon like structure provided with a body made up of relatively wide parallel side wall members 1 having a rectangular shaped frame 2, secured to the upper portions thereof, and the side members have axles 3 journaled therein and bridging the same to extend therethrough, with wheels 4 keyed or otherwise fixed to the outer ends of the axles, as best shown in Figure 2.

Secured to the side members of the frame 2 and rising therefrom for disposal in superimposed relation with respect to the front and rear axles, are pairs of relatively short uprights 5, with the uprights of each pair disposed in parallelism with each other, as shown, and bridging the uprights 5 are rods 6, there being a pair of rods for each pair of uprights, with the rods of each pair of uprights disposed in superposed relation with respect to each other and fixed thereto.

Mounted on each pair of rods 6 is a pair of relatively long uprights 7 providing what I term trapeze poles, and it will be noted as best shown

in Figure 2, that the uprights 7 are provided with bearing openings 8 extending transversely therethrough and through which extends the upper rods, while the lower rods extend through slots 9 disposed longitudinally of the uprights 7. The bearing openings are outwardly flared from the centers thereof, to allow for a rocking movement of the uprights 7 on the upper rods, which act as a fulcrum therefor, so that upon rocking movement of the uprights 7, the upper and lower ends thereof will be moved toward and away from each other, but the uprights 7 are held against slidable movement on the upper rods 6 by abutment pins 10 that extend transversely therethrough, as best shown in Figure 1, and it will be noted that the slots 9 are of sufficient length to allow for free rocking movement of the uprights 7.

The uprights 7 are of a length to extend a considerable distance above the fixed uprights 5 and bridging each pair of the uprights 7 is a twisted flexible strand 11 which is preferably a piece of cord that is fixed to the upper ends in taut condition. Each of the strands 11 have connected thereto and normally depending therefrom a jointed figure 12 shaped to simulate a trapeze performer and each figure includes a body having arm and leg members 13 and 14 respectively pivotally connected thereto, with a cross member 15 secured to and bridging the arms of each figure and which preferably have the strand extending therethrough and fixed therein, so that upon movement of the lower ends of the uprights 7, the upper ends will be moved in opposed directions to expand and contract the strands 11 which due to the twisted portions thereof will cause the figures to swing and perform acrobatic movements, as will be apparent.

In order to rock the uprights 7 to bring about the movement thereof for the purpose set forth, I provide disk members 16 fixed to each of the axles, and formed on the confronting faces of the disk members 16 are undulated cam surfaces 17 for disposal in the path of rollers 18 journaled on pins 19 secured to and depending from the lower ends of the uprights 7, as best shown in Figure 2.

The disk members 16 also act as abutment means for the body of the wagon structure, and as the rollers 18 contact the cam surfaces, the body will be held in spaced relation with respect to the wheels. The ends of the body are preferably reduced for disposal inwardly from the upper portions thereof, and the forward end of the frame 2 has secured thereto the bracket members 20 with a pin bridging the same, and a

handle 21 is pivotally connected to the pin to be used for propelling the toy as will be apparent.

From the above description and disclosure of the drawing, it is believed that it will be obvious that either a forward or backward propelling movement of the toy through the medium of the handle 21, will result in the figures performing their acrobatic movements, as upon rotation of the disk member 16, in either direction, pressure will be applied and released with respect to the lower ends of the uprights 7 by the undulated cam surfaces, for rocking the uprights 7, to expand and contract the strands 11, so as to wind and unwind the twisted portions thereof to bring about the movement of the figures as set forth.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A toy comprising a body, ground engaging wheels for said body, uprights carried by said body and fulcrumed for rocking movement, flexible means bridging the upper ends of said uprights and secured thereto in taut condition, a jointed figure fixed to the flexible means and the latter being twisted to cause swinging movement of the figure upon rocking movement of the uprights, and means for rocking the uprights and operated from the wheels upon forward and backward movement of the toy.

2. A toy comprising a body, axles journaled to the body, ground engaging wheels fixed to the axles, uprights carried by said body and fulcrumed for rocking movement, flexible means bridging the upper ends of said uprights and secured thereto in taut condition, jointed figures fixed to the flexible means and the latter being twisted to cause swinging movement of the figures upon rocking movement of the uprights, cam means fixed to the axles, and means on the lower ends of the uprights and engaged with the cam means for rocking the uprights upon forward and backward movement of the toy.

3. A toy comprising a body, axles journaled to the body, ground engaging wheels fixed to the axles, means secured to and rising from the body, superimposed rods bridging and secured to

the rising means, uprights mounted for rocking movement on the upper rods and slidable movement on the lower rods, flexible means bridging the upper ends of said uprights and secured thereto in taut condition, jointed figures fixed to the flexible means and the latter being twisted to cause swinging movement of the figures upon rocking movement of the uprights, and means secured to the axles and having the lower ends of the uprights engaged therewith for rocking said uprights upon forward and backward movement of the toy.

4. A toy comprising a body, axles journaled to the body, ground engaging wheels fixed to the axles, means secured to and rising from the body, superimposed rods bridging and secured to the rising means, uprights mounted for rocking movement on the upper rods and for slidable movement on the lower rods, flexible means bridging the upper ends of said uprights and secured thereto in taut condition, jointed figures fixed to the flexible means and the latter being twisted to cause swinging movement of the figures upon rocking movement of the uprights, undulated cam members fixed to the axles, rollers journaled to the lower ends of the uprights and engaged with the cam members for rocking the uprights upon forward and backward movement of the toy, and a handle for the toy and pivotally secured to the body.

5. A toy comprising a body, ground engaging wheels for said body, relatively short uprights secured to said body, superimposed rods bridging the uprights and secured thereto, relatively long uprights having bearing openings therein with the upper rods extending therethrough, said bearing openings being shaped for rocking movement of the long uprights on the upper rods, said long uprights having slots extending longitudinally thereof with the lower rods extending through the slots for slidable movement of the long uprights on the lower rods, flexible means bridging the upper ends of the long uprights and secured thereto in taut condition, jointed figures fixed to the flexible means and the latter being twisted to cause swinging movement of the figures upon rocking movement of the long uprights, means for rocking the long uprights and operated from the wheels upon forward and backward movement of the toy, and a handle for the body.

RICHARD REGENBURGH, SR.
